UNITED STATES PATENT OFFICE.

HENRY E. PARSON AND GEORGE V. NORTHEY, OF NEW YORK, N. Y.

APPARATUS FOR HEATING AND DRYING BARRELS.

SPECIFICATION forming part of Letters Patent No. 241,711, dated May 17, 1881.

Application filed December 22, 1880. (No model.)

To all whom it may concern:

Be it known that we, HENRY E. PARSON and GEORGE V. NORTHEY, of the city, county, and State of New York, have invented certain new and useful Improvements in Apparatus for Heating and Drying Barrels, of which the following is a specification.

The barrels manufactured in coopering establishments and used for petroleum, flour, and other purposes, were heretofore dried by exposing them to the heat of a wood fire, which was kept up within an open sheet-metal cylinder, that is technically known as the "cresset," or to the heat of a coal or wood stove having a closed cresset, in the use of which only the indirect action of the fire is obtained. The former method is objectionable on account of the slow and uneven heating of the barrels, owing to the difficulty of keeping up a good regular fire. The latter is objectionable on economical grounds.

The object of our invention is to provide a heating and drying apparatus in which naphtha is used, and by which a larger number of barrels can be quickly, cheaply, and uniformly dried.

The invention consists of a retort to which naphtha is supplied under pressure, the retort being heated by means of a vapor-burner in the nature of a Bunsen burner, which is regulated by means of a needle-valve. The retort is supported by the oil-supply and gas-conducting pipes, with which it forms a kind of yoke across the burner, the pipes being provided at their lower ends with detachable receptacles or sacks for taking up the gummy sediments of the retort. A cylindrical cresset is locked to the platform which encircles the gas-generating and heating apparatus by an annular flange and fulcrumed and weighted locking-hooks, the latter entering recesses of the cresset. The cresset carries at its upper end an exterior deflecting-plate of larger diameter and at the inside of the cresset a second deflecting-plate of smaller diameter than the cresset.

In the accompanying drawings, Figure 1 represents a vertical central section of an improved apparatus for heating and drying barrels. Fig. 2 is a horizontal section of the same on line *xx*, Fig. 1; and Fig. 3 is a detail verti-

cal transverse section through the retort, on line *yy*, Fig. 2.

Similar letters of reference indicate corresponding parts.

55

Referring to the drawings, A represents a hydrocarbon-retort of semicircular cross-section, which is supplied with naphtha or other light hydrocarbon-oil under pressure from a suitable reservoir by a conduit-pipe, B, and an upwardly-extending pipe, B', the latter being jointed to one end of the retort. A second pipe, C, extends from the opposite end of the retort downward to a level with the conduit-pipe B, the pipes B' and C forming a yoke-shaped support for the retort A.

From the downwardly-extending pipe C extends, at a level with the supply-pipe B, a short horizontal pipe, C', which conducts the vapors generated in the retort to a vertical needle-valve, D, which needle-valve is adjusted up or down by its threaded shank and a hand-wheel at its lower end, so as to more or less open or close the issuing orifice or throat of its valve-cylinder. The hydrocarbon vapors are forced with considerable pressure through the throat of the needle-valve, and into the cylindrical mixing-tube D', which is arranged vertically above and axially in line with the needle-valve, the mixing-tube D' being supported below the retort A by a cup-shaped diaphragm, b, of the yoke. At the lower ends of the pipes B and C are arranged receptacles or sacks E, which take up the gummy sediments that are formed in the retort, as they are conveyed downward along the walls of the vapor-conducting pipe C and oil-supply pipe B'. These receptacles or sacks are unscrewed from time to time for removing the sediments.

For readily cleaning the retort A, as well as the pipes B' and C, the former is provided with tightly-fitting screw-plugs *d d* at the ends, and with screw-plugs *d' d'* at the top part, in line with pipes B' and C, so that by unscrewing the plugs *d d'* and the sacks E the retort and the supporting-pipes B' C can be cleaned of all sediments by means of brushes or other devices.

The gas-generating apparatus just described is preferably arranged in the central wall of a brick platform, F, so that in case any naphtha should escape by leakage of the joints it is col-

lected in the lower part of the well, and thereby spreading and danger of fire are obviated. There is room enough at both sides of the apparatus to admit the unscrewing of the sediment-sacks as well as the adjustment of the needle-valve.

Upon the brick platform is supported a ring-shaped plate, *e*, which is provided with an annular flange, *e'*, to which are fulcrumed at diametrically opposite points weighted locking-hooks *f*, which extend to the inside of the cresset *G* and engage slotted openings at the lower part of the same, so as to lock it rigidly between the flange *e'* and the hooks *f* by just setting it in position within the flange. By lifting the weighted arms of the locking-hooks the cresset can be readily removed, and thereby access to the interior of the apparatus obtained.

At the upper part of the cresset *G* is supported, on suitable brackets or stays, a disk-shaped deflecting-plate, *G'*, of larger diameter than the cresset. From this disk is suspended, by a center rod, a second supplementary disk, *G²*, which is of smaller diameter than the cresset, and supported intermediately between the retort and the outer larger disk.

The apparatus is operated as follows: The barrels are placed in position upon the platform, so as to encircle the cresset, in which position they are acted upon by the circular sheet of flame which issues through the annular space between the upper deflector and the top edge of the cresset. The heating-flame is obtained by the generation of hydrocarbon vapors in the retort, which vapors, after passing through tubes *C* and *C'*, are delivered to the needle-valve *D*, forced through the throat *a*, thence through the mixing-tube *D'*, into which the air is drawn on the principle of an injector. The air and gas mixture burns with a heating-flame at the upper end of the burner-tube *D'*, and impinges upon the flat bottom part of the retort, so as to heat the retort and keep up the generation of gas. The flame is divided by the retort into two parts, which are impelled nearly at right angles against the wall of the cresset, from which they are deflected in an upward direction and intercepted by the interior deflecting-plate, which throws them again back upon the upper wall of the cresset, where they are deflected against the upper deflector, and finally emitted through the annular space formed between the top edge of the cresset and the upper deflector. By these repeated deflections of the heating-flame a continuous mixing of the gases with the atmospheric air, and consequently a thorough combustion of the vapors, is obtained, so that a high degree of heat is the result. As the cresset is thoroughly heated up by the combustion of the gases it exerts an effective heating influence upon the barrels by radiation, while the burning vapors, which pass out at the upper part of the cresset, retain the heat in the space between barrel and cresset, and secure an even and rapid drying of the staves.

By this apparatus a uniform high temperature may be maintained throughout, and the barrels be heated and dried in a quicker manner than heretofore, without the loss of time incidental to the starting and extinguishing of wood fires. The apparatus is quickly set in operation by simply supplying the asbestos filling of the cups of needle-valve and mixing-tube with naphtha, as customary in vapor-burners, it being, after starting, kept up by the vapors generated in the retort.

The gas-generating and heating apparatus may also be used for cooking, heating, and other purposes, in which cases, however, the shape of the cresset has to be changed, or a second exterior cylinder or jacket be provided.

Having thus described our invention, we claim as new and desire to secure by Letters Patent—

1. The combination, in an apparatus for heating and drying barrels, of a hydrocarbon-gas-generating retort, a burner beneath the same, and an open cresset encircling said retort and burner, provided with a deflector, between which and the cresset is an opening for the products of combustion, substantially as described.

2. The combination of a supporting-platform having a central well, a gas-generating retort, vertical oil and vapor conducting pipes supporting the retort and extending into the well, and a vapor-burner below the retort, substantially as described.

3. The combination of a supporting-platform having a central well, a gas-generating retort having supporting-pipes extending into the well, a vapor-burner below the retort, and a cresset supported upon the platform and encircling the retort and burner, substantially as described.

4. The combination, with a cresset, of a gas-generating retort and vertical oil and vapor conducting pipes connected therewith, said pipes being provided at their lower ends with detachable sediment-receptacles, and connected above said receptacles with branch oil-supply and vapor-conveying pipes, substantially as described.

5. In an apparatus for heating and drying barrels, the combination of a supporting-platform having a central well with a cresset supported thereon, and with means whereby the cresset is detachably connected to the platform, substantially as set forth.

6. In an apparatus for heating and drying barrels, the combination of a supporting-platform having an annular flange, and weighted locking hooks fulcrumed to the flange, with a cresset having slots at the lower part for the locking-hooks, as set forth.

7. In an apparatus for heating and drying barrels, the combination, with the cresset, of a deflecting-plate at the upper part of the same, said deflector being of larger diameter than the cresset, substantially as set forth.

8. In an apparatus for heating and drying barrels, the combination of a cresset with an exterior deflecting-plate of larger diameter

and with an interior deflecting-plate of smaller diameter than the cresset, substantially as specified.

9. The combination of a generating-retort supported by conducting-pipes, and a heating vapor-burner below the retort, with an encircling cresset having an interior deflector above the retort, substantially as set forth.

10. The combination, with a cresset, of a gas-generating retort provided with vertical oil and vapor conducting pipes which enter its bottom, and with plugged openings at its top,

opposite the entrance of the pipes, said pipes having detachable sediment-receptacles at their lower ends, substantially as described. 15

In testimony that we claim the foregoing as our invention we have signed our names, in presence of two witnesses, this 20th day of December, 1880.

HENRY E. PARSON.
GEORGE V. NORTHEY.
